[57] CLAIM

The ornamental design for a drum lug, substantially as shown and described.

DESCRIPTION

FIG. 1 is a front elevational view of a drum lug showing my new design;

FIG. 2 is a right side elevational view, the left side being a mirror image thereof; and

FIG. 3 is a top plan view, the bottom being identical. The surfaces opposite those shown in FIG. 1 are conventionally plain.

Fig. 1.

Fig. 2.

Fig. 3.
